UNITED STATES PATENT OFFICE

2,546,581

HYDRAULIC APPARATUS

Cecil E. Adams, Columbus, Ohio, assignor to The Denison Engineering Company, Columbus, Ohio, a corporation of Ohio

Application July 18, 1947, Serial No. 761,973

18 Claims. (Cl. 60—52)

1

This invention relates to hydraulic apparatus and is particularly directed to an improved hydraulic system for use in a hydraulic machine having a plurality of movable elements operated in sequence.

One of the objects of the present invention is to provide a hydraulic circuit containing a plurality of fluid motors, each having a control mechanism which is so constructed and connected in the system as to secure a desired sequence of operation of the fluid motors.

Another object is to provide a hydraulic system containing a plurality of reversible fluid motors and to provide each of the motors with a control mechanism which functions to cause a complete cycle of operation of the fluid motor controlled thereby and then direct fluid under pressure to the next control mechanism while restraining or locking its fluid motor against further operation until all of the motors have been operated in the desired sequence.

A still further object of the invention is to provide a hydraulic system containing a plurality of reversible fluid motors, each having a control mechanism with a pressure-responsive motor-controlling element operative to direct fluid to certain portions of the circuit; one of the pressure responsive elements serving to initiate operation of a fluid motor and a second serving to direct fluid pressure to the fluid pressure responsive element of the first control mechanism upon the conclusion of operation of the motor controlled by the second pressure responsive element.

A further object is to provide a hydraulic system with a plurality of power cylinders having reciprocating pistons and to provide one or more of the power cylinders with control mechanism which will cause the piston in a power cylinder to reciprocate in a certain manner and then function to direct fluid to the control mechanism of another power cylinder, thus governing the sequence of operation of the power cylinders.

It is also an object of the invention to provide a novel hydraulic system for a press having a ram, an index table, and a feeding device, the system having control valve mechanism operative to cause the feeding device to function to dispose work on the index table; cause the table to operate to register the work with the ram; cause the latter to exert a pressing force on the work and then be retracted from the work and cause a repetition of the foregoing cycle of operations, the control mechanism being so constructed that each operating device will complete

2

one cycle of operation and then be held in inoperative condition until the other devices have each completed one cycle of operation.

Another object of the invention is to provide a hydraulic system for a press of the type mentioned in the preceding object in which the control valve mechanism for the ram and the feeding device will cause a rapid vibration or agitation of the movable elements of these devices whereby improved products will be produced in the press.

Other objects and advantages will be apparent from the following description of one embodiment of the invention illustrated in detail in the accompanying drawings.

In the drawings:

Fig. 1 is a front elevational view of a hydraulic press formed in accordance with the present invention, this press being provided with an index table and a hydraulic feeding mechanism, the press ram, the index table and feeding mechanism being operated in sequence.

Fig. 2 is a diagrammatic view of the hydraulic system employed in the mechanism shown in Fig. 1 to effect the operation of the press ram, index table and feeding mechanism, the parts of the circuit controlling mechanism being disposed in the positions occupied when the press and attachments are idle.

Fig. 3 is a similar view of the press controlling portion of the hydraulic system showing the mechanism in position to initiate a cycle of operation of the press and attachments.

Fig. 4 is a diagrammatic view of the index table portion of the hydraulic system showing parts thereof in positions occupied during controlled operation of the index table.

Fig. 5 is a similar view of the same portion of the hydraulic system showing parts in the position occupied immediately after the conclusion of a table-indexing operation and in condition to initiate a cycle of operation of the feeding mechanism.

Fig. 6 is a diagrammatic view of the feeding mechanism control section of the circuit, the parts being in the positions occupied during operation of the feeding mechanism.

Fig. 6A is a similar view of the feeding mechanism control section of the circuit, the parts being in the positions occupied during the return stroke of the piston which operates the feeding mechanism.

Fig. 7 is a similar view of the same mechanism showing the parts at the conclusion of the feed-

ing operation and in condition to initiate an operation of the press ram.

Fig. 8 is a diagrammatic view of the press-control section of the circuit showing the parts in the positions occupied during the performance of a working stroke of the press ram.

Fig. 9 is a diagrammatic view of a modified press control valve mechanism through the use of which short vibratory strokes of the press ram may be secured.

Fig. 10 is a similar view of a similarly modified feeding apparatus control valve mechanism with which the feeding tools may be vibrated to give improved performance.

Referring more particularly to the drawings, the number 20 designates the apparatus in its entirety. This apparatus includes a press 21 which is of the type known as a C-frame press having a base section 22, an upright section 23, and a head section 24 in which a ram 25 is mounted for reciprocation. The base of the press in this instance is provided with a hydraulic index table 26 and a feeding mechanism indicated generally by the number 27, the latter mechanism being provided to move work onto the index table at the various stations thereon, the table serving to move such work into registration with the ram 25 to have a pressing operation performed thereon.

The elements making up this combination are all hydraulically operated and means are provided to cause such elements to operate in the proper sequence, that is, the feeding mechanism functions to move the work on to the index table, the index table then moves the work into registration with the ram and the latter then performs a pressing operation after which the cycle is repeated, the movement of the table serving to move the work, which has been pressed, out of registration with the ram while the next piece of work is being moved into registration therewith.

This apparatus performs these operations automatically through the use of a hydraulic system illustrated diagrammatically in various figures of the drawings, the complete system being disclosed in the idle stage in Fig. 2 of the drawings. From this figure it will be noted that the hydraulic system includes a source of fluid pressure having a reservoir 30, a power driven pump 31, a relief valve 32 and fluid lines 33, 34, and 35 to conduct fluid from the reservoir to the pump and from the pump to the relief valve, the line 35 conducting fluid from such valve back to the reservoir when the fluid pressure in the system reaches a predetermined figure. The hydraulic system also includes valve mechanism, indicated generally by the number 36, for controlling the operation of the ram 25. The control mechanism 36 may be of many types, the one illustrated being of the type shown in my co-pending application, Serial No. 589,163, filed April 19, 1945, now Patent 2,491,355 issued December 13, 1949. Ram 25 is connected to a piston 37 disposed for reciprocation in a cylinder 38, the cylinder and the valve mechanism 36 being located in the head section 24 of the press 21.

It will be apparent from Fig. 2 that the hydraulic system also includes control mechanism 40 for the hydraulic index table 26. This index and control mechanism has been illustrated and described in detail in my co-pending application, Serial No. 690,184, filed August 13, 1946. The index table is of the intermittently operated type and, as in the above-mentioned co-pending

application, includes a hydraulic motor 41, the operating shaft of which is provided with a pinion 42 disposed in meshing engagement with a gear 43, this gear being secured to, or forming a part of, the driver of a Geneva gear employed to intermittently operate the index table. The gear 43 has a cam track 44 secured to its under surface for engagement by a roller 45 journaled on the outer end of a pusher rod 46; this pusher rod forms a part of the control mechanism 40. As shown in Fig. 2 the feeding mechanism 27 includes a ram 47 which is connected with a piston 48 disposed for reciprocatory movement in a cylinder 50. The movements of the piston 48 and the ram 47 are governed by a control mechanism indicated generally by the numeral 51. Numerous lines connect various ports of the control valve mechanisms for both rams and the index table to complete the hydraulic system.

Line 34, which leads from the source of fluid pressure, extends to the inlet of the valve mechanism 36. This valve mechanism has been set forth in detail in co-pending application Serial No. 589,163, filed April 19, 1945, and will only be described generally herein. This mechanism includes a sleeve 53 disposed for sliding movement in a bore 54 formed in a valve body 55, the sleeve being provided with a series of lateral ports 56 to 62, inclusive, which are arranged to communicate, either continuously or at certain intervals, with grooves 63 to 68, inclusive, also formed in the valve body 55 around bore 54. The sleeve 53 receives for sliding movement, a shuttle valve 70 which is provided with longitudinal spaced reduced portions 72 to 75, inclusive. The valve body 55 is also provided with a second bore 76 for the reception of a spool 77 used in starting and stopping the apparatus and in causing the automatic repetition of the cycle of operation. Recesses 78 to 81 are formed in the body 55 in communication with the bore 76. When the parts of the mechanism 36 are disposed as shown in Fig. 2 while the pump 31 is in operation, fluid will flow from line 34 into groove 66, through ports 60 to the interior of the sleeve 53 and downwardly around the reduced portion 74 of the shuttle valve to ports 59 in the sleeve. This fluid will flow through these ports 59 to groove 65 from which it will flow to recess 79 and bore 76, the fluid flowing upwardly in this bore and outwardly therefrom through recess 80, to groove 67 and through ports 61, to the interior of the sleeve 53 at the upper end of the shuttle valve. This fluid may then flow to the reservoir 30 through ports 62, groove 68, recess 81, and line 32. It will be obvious that when the press is idle, the pump 31 will operate without load since the fluid is bypassed directly to the reservoir. Spool 77 is normally held in position to bypass fluid to the reservoir by coil springs 83 and 84 located at the opposite ends thereof, these springs tending to hold the spool in a centered position.

The valve mechanism 36 has an eccentric pin 85 journaled in the body 55 as at 86 to effect the movement of the spool 77 in the operation of the mechanism, the pin 85 being governed through the operation of a hand lever shown at 87 in Fig. 1. When it is desired to initiate a cycle of operation of the apparatus, the hand lever 87 is moved to the position in which spool 77 will be located as shown in Fig. 3, in which location a head 88 at the upper end thereof will interrupt communication between bore 76 and recess 80. This interruption will cause fluid pressure, supplied to the mechanism 36, to be directed from

recess 79 through line 89 which extends to the control mechanism 40 for the fluid motor of the index table.

Line 89 leads to the inlet of the control mechanism 40 which inlet communicates with a bore 90 formed in the body of the mechanism. This bore 90 is provided with a plurality of annular grooves 91 to 95, inclusive, groove 94 being connected with the line 89 and receiving fluid flowing to the mechanism therethrough. This fluid flows from groove 94 through bore 90, to groove 93 and outwardly therefrom through passage 96 to the inlet of fluid motor 41. The outlet of this motor is connected directly with reservoir 30 by a line 97, this line containing a variable orifice 98 used to control the speed of operation of the motor 41. The body of control mechanism 40 includes a second bore 99, this bore receiving a spool 100. A spring 101 tends to urge this spool in an upward direction, holding the upper end thereof in engagement with the inner end of the the pusher rod 46. When the apparatus is idle, as shown in Fig. 2, the roller 45, carried by the pusher 46, will be disposed on the cam track 44 in the position shown in Fig. 2, this position being such as to retain the spool 100 partially depressed against the action of the spring 101 in which position grooves 102 and 103 surrounding bore 99 will be connected by groove 104 of the spool 100.

At this time a branch line 105 leading from line 97 will be connected directly to tank 30 through grooves 102 and 103 so that fluid being discharged from the fluid motor 41 will bypass the variable orifice 98. When this orifice is bypassed in this manner, fluid motor 41 will receive the full pump volume and operate at full speed, the operation of the motor causing a rotation of pinion 42 and gear 43 together with the cam track 44. As this cam track revolves, a depression 106 therein will register with roller 45 permitting spring 101 to force spool 100 and pusher 46 in an upward direction. As spool 100 moves upward, the unreduced lower portion 107 thereof will interrupt communication between grooves 102 and 103 causing the fluid discharged from fluid motor to flow through the orifice 98. If properly adjusted, this orifice will cause a pressure drop, the higher pressure of which will be conducted through line 105, groove 102, and line 108 to the upper end of bore 90. This fluid pressure will be applied to the upper end of spool 109, which is disposed for sliding movement in bore 90, causing this spool to be depressed until a groove 110 formed therein establishes communication between grooves 93 and 92 of bore 88, the latter groove being connected by line 111 with reservoir 30. When spool 109 is depressed in this manner, a portion of the fluid introduced to the control mechanism 40 through line 89 will be bypassed to the reservoir and fluid motor 41 will be caused to operate at a controlled slower speed. While operating at this controlled speed the fluid motor will cause the table 26 to index one step. Upon the completion of this indexing step cam 44 will again depress spool 100 to a position wherein grooves 102 and 103 will be connected and fluid may bypass the orifice 98 destroying the pressure differential. This action will permit spool 109 to return to its central position to which it is normally urged by springs 112 and 113, interrupting the communication between grooves 93 and 92 and causing full pump volume to be directed to the fluid motor 41. This motor will then oper-

ate at full speed causing the rapid rotation of the gear 43.

Cam 44 has a projection 114 which engages roller 45 and depresses push rod 48, this member in turn depressing spool 100 to the position shown in Fig. 5. When the spool 100 is thus depressed the reduced upper end 115 thereof will establish communication between grooves 116 and 117 and fluid flowing to the mechanism through line 89 will be directed into line 118 which leads to the control mechanism 51 for the feeding device. Line 118 is also connected with the lower end of the bore 90 and fluid pressure supplied to this line will flow into the bore 90 beneath spool 109 forcing the same upwardly into the position shown in Fig. 5, wherein grooves 93 and 92 will be connected by recesses on the sides of the spool thus establishing communication between the fluid motor inlet line 96 and reservoir 30.

When spool 100 is fully depressed by projection 114, grooves 102 and 103 will also be connected establishing communication directly between the line 105, which is connected with the outlet port of the fluid motor, and reservoir 30. Since both inlet and outlet ports of the fluid motor 41 are connected directly with the reservoir, the operation of this motor will be discontinued. The momentum of the driver 43, and motor 41 will be sufficient to cause the projection 114 to pass slightly beyond the roller 45 and the fluid pressure then existing in groove 117 will be sufficient to exert an upward force on push rod 48 to return the same to its elevated position, such fluid pressure also serving to hold spool 100 depressed against the action of spring 101. As long as fluid under pressure is supplied to line 89, spool 100 will be held depressed to direct fluid from line 89 to line 118 which leads to the control mechanism 51 of the feeding device 27 which control mechanism corresponds in operation somewhat to the operation of the valve disclosed in my co-pending application Serial No. 589,163.

Mechanism 51 includes a body 120 having a pair of parallel bores 121 and 122, the former receiving a sleeve member 123 which has a plurality of longitudinally spaced transverse ports 124 to 130, inclusive, these ports being adapted to communicate in certain positions of the sleeve 123 in bore 121 with annular grooves 132 to 137, inclusive, formed in the body 120 around bore 121. Sleeve 123 receives, for sliding movement, a shuttle valve 142 which corresponds to the shuttle valve 13 in the valve mechanism 36, the valve 142 having longitudinally spaced annular relieved portions 143 to 146, inclusive. Valve 142 is normally held in its forward position, as disclosed in Fig. 2, by coil spring 147 arranged in sockets formed in the valve member and cap 148 carried by the upper end of the sleeve. When valve 142 is in the position shown in Fig. 2, relieved portion 145 will establish communication between ports 128 and 127, the former communicating with groove 135 to which fluid is supplied through line 118, and the latter communicating with groove 134 which connects with a recess 150 formed in the body in communication with the bore 122. This bore 122 has a liner 151 positioned therein which liner has a port 152 in communication with the recess 150. The liner receives a spool 153 and pusher piston 154, the former having a relieved portion 155 which establishes communication between port 152 and ports 156 leading through the liner 151 to groove 157 which is connected by port 158 with groove 132. Thus, fluid flowing to the control mech-

anism through line 118 will be conducted through groove 135, ports 128 and 127, groove 134, recess 150, ports 152 and 156, groove 157, and port 158 to groove 132, this groove being connected by ports 124 with the interior of the sleeve 123 at the forward end of the shuttle valve 142. Fluid introduced into the sleeve in this manner will cause the shuttle valve 142 to move rearwardly against the force of the spring 147 to the position shown in Figs. 6 and 6A, to establish communication between ports 128 and 129. At this time fluid supplied through line 118 will then be directed to groove 136 from which it will flow through line 160 to the rear end of cylinder 50. This fluid will apply force to the rear end of piston 48 causing the same to move in a forward direction in a feeding operation. Any suitable feeding instrument may be secured to the forward end of the feeder ram 47, a measuring box 161 being shown in Fig. 1 for the purpose of illustration only, such box being employed when the press is used to form articles from powdered materials, to transfer powder from the hopper to molds carried on the index table.

During the forward movement of piston 48 fluid will be discharged from the forward end of the cylinder 50 through line 162 to groove 133 from which it will flow through ports 125 to the interior of the sleeve 123 and into the interior of the shuttle valve through ports 163 formed in the reduced portion 164 of valve 142. This fluid flows longitudinally through the shuttle valve 142 and outwardly from the sleeve 123 through ports 130 to groove 137 from which it will flow to the adjacent end of bore 122 and thence to reservoir 30 by way of line 164. Due to the reduced size of the longitudinal bore at 165 in shuttle valve 142, the exhaust flow of fluid from cylinder 50 will be restricted causing a back pressure. The force of this pressure is transmitted through the orifice 166 in the forward end of shuttle valve 142 to the interior of the sleeve 123 at the forward end of the shuttle valve. The reaction of this fluid pressure retains the shuttle valve against the force of spring 147 as long as piston 48 is moving in a forward direction. While shuttle valve is held in this position, fluid admitted through line 118 will be directed to the rear end of cylinder 50. Sleeve 123 is shown in its rearward position in Fig. 2 to which it is moved when piston 48 is retracted, the movement of the piston being transmitted to the sleeve 123 through an arm 167 and a shipper rod 168 projecting from the forward end of the sleeve 123. This shipper rod carries a collar 169 which the arm 167 engages immediately prior to reaching its fully retracted position. After engaging the collar 169, continued movement of the piston 48 and arm 167 will move the sleeve rearwardly until fluid flow to the forward end of the cylinder 50 is interrupted. In moving to this position, a coil spring 170, which is disposed between a washer 171 and a collar 170A surrounding shipper rod 168 within the valve casing, will be compressed. As soon as arm 167 starts moving forward, this spring 170 will return the sleeve 123 to its normal centered position, as shown in Fig. 6. When the sleeve 123 occupies this forward position, the ports 126 will communicate with groove 133 and the exhaust of fluid from cylinder 50 will function in the same manner to retain the shuttle valve against the spring 147 to cause forward movement of piston 48 and ram 47.

When the ram 47 reaches the forward end of its working stroke, piston 48 will engage the end wall of cylinder 50 and further movement will

be prevented. When piston 48 stops, the back pressure in the exhaust line will fall permitting pressure beneath shuttle 142 to be dissipated and spring 147 will move the shuttle valve 142 to its forward position as shown in Figs. 6 and 7. At this time, fluid supplied to control mechanism 51 through line 118 will be directed by the shuttle valve 142 from groove 135 to groove 133, this groove being connected with the forward end of the cylinder 50 by line 162. When fluid pressure is supplied in this manner to the forward end of cylinder 50 the force of this fluid will urge piston 48 in a rearward direction. This movement of piston 48 will discharge fluid from the rear end of cylinder 50 into line 160 which leads to groove 136. When the shuttle valve 142 is disposed in its forward position, and sleeve 123 is centered by spring 170 as shown in Fig. 6A, groove 136 will be connected through ports 129, the interior of the sleeve 123, and ports 130, to groove 137 which in turn is connected with the fluid reservoir 30 by the end of bore 122 and line 164. Thus, rearward movement of piston 48 will cause fluid to be discharged from the rear end of cylinder 50 to the reservoir.

Line 160 is provided with an orifice 171A which operates to resist the discharge of fluid through line 160. This resistance to fluid flow creates a back pressure which is transmitted by a branch line 172 to the forward end of bore 122. This back pressure is applied to piston 154 causing the same to move rearwardly and impart similar movement to spool 153 in opposition to force exerted by coil spring 173. Movement of this spool is limited through the engagement of the rear end thereof with the end wall of the bore 122. The spool 153 will then be disposed in the position shown in Fig. 7, in which position a transverse passage 174 formed in the spool registers with ports 175 in liner 151. During the rearward movement of piston 48, this back pressure in line 160 will continue to hold piston 154 and spool 153 in the rearward position. Near the termination of rearward movement of piston 48, arm 167 will engage collar 169 on shipper rod 168 and continued movement of piston 48 will cause rearward movement of sleeve 123, from the normal centered position shown in Figs. 6 and 6A, to the rearward position shown in Figs. 2 and 7. In this position, fluid flow from line 118 to the forward end of cylinder 50 will be interrupted, such fluid then being directed through ports 128 and 127, and through groove 134, to recess 150. When the spool 153 is held in its rearward position as shown in Fig. 7 the relieved portion 155 establishes communication between recess 150 and ports 175 in sleeve 151. Since transverse passage 174 connects ports 175, fluid from groove 150 will also be admitted to passage 174 at this time. Ports 175 are connected by slot 176 in sleeve 151 with port 177 which is formed in the valve-body 120, this port being connected by line 178 with groove 63 in the body of valve 36. Fluid supplied under pressure in this manner to line 178 will thus be directed through ports 56 to the interior of sleeve 53 beneath shuttle valve 70. The force of this fluid will move this shuttle valve against the opposition of its spring to the elevated position shown in Fig. 8 in which position fluid from the inlet line 34 will be directed through ports 61 to groove 67, which is connected by line 180 with the upper end of power cylinder 38. A cycle of operation of ram 25 will thus be initiated.

As the piston 37 in cylinder 38 moves in a downward direction in response to the admission of

fluid through line 180, fluid will be discharged from the lower end of cylinder 38 through line 181 to groove 64, this fluid flowing through ports 58 into transverse ports 182 formed in shuttle 70 at the reduced portion 73, and longitudinally of the shuttle to ports 62 which are connected with the reservoir 30 by recesses 68 and 81 and exhaust line 82. The passage in the shuttle valve 70 is restricted at 183 to create back pressure on the exhausting fluid, which back pressure is transmitted through an orifice 184 in the shuttle valve 70 to the space in sleeve 53 beneath such shuttle valve 70 and retains the latter in position to direct fluid from the pressure source to the upper end of the power cylinder 38. Immediately upon the initiation of a downward stroke of the ram 25 an arm 185 thereon moves away from collar 186 permitting spring 187 to move sleeve 53 to a centered position. During the movement, ports 59 will be moved out of registration with groove 65 and fluid, from the pressure source, will then be prevented from flowing to lines 83 and 118. Fluid pressure is maintained in this part of the system, however, by the back pressure admitted through orifice 184 in shuttle valve 70 to the chamber beneath the valve in sleeve 53 and to line 178 connected therewith. This fluid pressure is sufficient to retain shuttle valve 70 elevated and to hold spool 153 in its rearward position in opposition to the spring 173. This pressure is transmitted through line 178 to recess 177 and through ports 175 to passage 174. From this passage the pressure is transmitted through passage 188 to the forward end of the spool 153. This fluid pressure moves piston 154 forwardly to the position shown in Fig. 7 while retaining spool 153 in its rearward position. As long as piston 37 is moving in a downward direction, this back pressure will be maintained. The pressure in line 178 also obtains in line 118, which line communicates with the lower end of bore 99 beneath spool 109, and in bore 99 in grooves 116 and 117, this pressure serving to retain spool 110 depressed to maintain communication between grooves 116 and 117.

When ram 25 reaches the end of its power stroke which may be determined either through the engagement of piston 37 with the lower end of cylinder 38 or the engagement of ram 25 with an obstruction offering sufficient resistance to cause fluid in the supply source to be bypassed to reservoir 30 by relief valve 32, the piston will stop moving downward and exhaust flow through line 181 will be interrupted. The back pressure in this line will be dissipated to tank 30 permitting the shuttle 70 to lower, under the influence of its spring, and spool 109 to be centered. Spool 109 will be permitted to be raised by spring 101 to a position interrupting communication between grooves 116 and 117, and spool 153 will be permitted to move forwardly under the influence of spring 173 to a position wherein recess 150 and port 152 will be connected by the reduced portion of spool 153 with ports 156 so that fluid introduced to control mechanism 51 in a succeeding cycle of operation, through line 118, will be directed to the forward end of shuttle valve 142.

When shuttle valve 70 drops, fluid from the inlet line 34 will be directed to the lower end of cylinder 38 to move piston 37 and ram 25 in an upward direction. As ram 25 approaches the upper limit of its movement, arm 185 will engage collar 186 on the shipper rod 189 and move spool 53 to its elevated position where in communication will again be established between ports 59 and groove 65. If spool 77 has been returned to

the idle position shown in Fig. 2 the fluid flowing to groove 65 through ports 59 will be directed to the reservoir 30 as previously described and the press and other mechanism will then be retained in idle condition. If, however, spool 77 is permitted to remain in the depressed position shown in Fig. 3, the fluid supplied to recess 79 will be directed through line 89 to control mechanism 40 of the index table to initiate a succeeding cycle of operation of the apparatus, the control means for the index table being then in position to cause the operation of the fluid motor 41 and an indexing of the table.

In some instances it may be found desirable to have the ram 25 execute a series of successive short reciprocations or vibrations between the power stroke and the return stroke. If the press-control valve is of the type shown in my co-pending application Serial No. 594,963, filed May 20, 1945, now Patent No. 2,512,730, issued June 27, 1950, and illustrated diagrammatically in Fig. 9 in the present drawings, a proper adjustment of a control knob 190 thereon will cause the operation of ram 25 in such manner. To perform these operations, a portion of the fluid admitted through the inlet line 34, when the ram 25 is started in an upward direction, is directed through line 191 to the under side of the shuttle valve 70 in the manner described in said Patent No. 2,512,730. The application of this fluid to the shuttle valve causes the same to be elevated to reverse the direction of movement of piston 37 by directing fluid supplied through line 34 to the upper end of cylinder 38. When the ram and piston again reach the limit of their movement in a downward direction and fluid ceases to be exhausted from the lower end of the cylinder 38, shuttle valve will be forced downwardly to again direct fluid under pressure to the under side of piston 37. These short strokes may be repeated as many times as determined by a counting device 192, after which the direction of fluid through line 191 will be prevented and ram 25 and piston 37 will be permitted to move to the initial starting position.

It is also a feature of this invention to utilize a similar short stroke or vibratory operation of the feeding ram 41. This operation may be secured with a control valve mechanism 193 shown diagrammatically in Fig. 10. This mechanism corresponds quite closely to the control valve mechanism shown in Fig. 9 and operates to direct fluid under pressure from line 118 to the under side of shuttle valve 142 through lines 194 and 195 upon initial rearward movement of ram 41, to move the shuttle valve 142 in opposition to spring 147 to the position wherein fluid will be directed from line 118 to the rear end of cylinder 50 to again cause forward movement of piston 48 and ram 41.

Each time the piston 48 engages the end wall 60 of the cylinder 50, and fluid ceases to be exhausted from cylinder 50, spring 147 will cause shuttle valve 142 to move forwardly to connect the forward end of cylinder 50 with the supply line 118 and the rear end of this cylinder with reservoir 30 through line 160. Control mechanism 193 is supplied with an adjustment knob 196 to regulate the number of short strokes, this short stroke creating and regulating mechanism is similar to that disclosed in my said Patent No. 2,512,730. It includes a pair of spools 198 and 199 which are actuated by fluid pressure during each initial rearward movement of piston 41 to direct fluid under pressure to the end of shuttle valve 142 and to pump fluid into one end of a counting device 200. The latter device has a

spring-pressed spool 201 which is moved in opposition to the force of a spring 202 in a step-by-step manner by the fluid pumped by piston 199, until it reaches a position in which fluid flow from supply line 118 through lines 194 and 195 to the forward end of shuttle 142 will be interrupted. When this interruption occurs the shuttle valve 142 will remain in its forward position and ram 47 will then execute a complete return stroke. When sleeve 123 is moved rearwardly at the termination of the return stroke of ram 47, the cap 148 on the end of sleeve 123 will engage the end of a check valve 203 to open the same and permit spring 202 to move spool 201 and expel fluid from the end of its chamber, thus resetting the counting mechanism for a succeeding operation.

I claim:

1. In a hydraulic system, a source of fluid pressure; a plurality of fluid motors; a control valve mechanism for each of said motors, means connecting said control valve mechanisms in series in said system so that each succeeding valve mechanism receives fluid from the preceding one; means in each valve mechanism being operative upon the conclusion of a cycle of operation by the motor controlled thereby, to direct fluid to the next succeeding valve mechanism, the final valve mechanism directing fluid back to the first valve mechanism in such series to initiate operation of the fluid motor controlled thereby.

2. In a hydraulic system, a source of fluid pressure; a plurality of fluid motors; control valve mechanism for each of said motors, said control valve mechanisms being connected in series in said system; fluid directing means in the first valve mechanism in said system, said fluid directing means being responsive to fluid pressure to initiate the operation of the motor controlled by said first valve mechanism, each valve mechanism being operative upon the conclusion of a cycle of operation by the motor controlled thereby, to direct fluid to the next succeeding mechanism; and means in said system connecting the final to the first valve mechanism and by-passing the intermediate mechanism, said means serving to apply fluid from the final valve mechanism to said fluid directing means in the first valve to initiate operation of the fluid motor controlled thereby.

3. In a hydraulic system, a source of fluid pressure; a plurality of fluid motors; control valve mechanism for each of said motors, said control valve mechanisms being connected in series in said system; fluid directing means in the first valve mechanism in said system, said fluid directing means being responsive to fluid pressure to initiate the operation of the motor controlled by said first valve mechanism, each valve mechanism being operative upon the conclusion of a cycle of operation by the motor controlled thereby, to direct fluid to the next succeeding mechanism; means in the second and succeeding valves in said system, operated by fluid pressure to lock said mechanism upon the completion of a cycle of operation of the motor governed thereby to prevent further operation of said motor; means in said system connecting the final to the first valve mechanism, said means by-passing the intermediate mechanism and serving to apply fluid from the final valve mechanism to said fluid directing means in the first valve to initiate operation of the fluid motor controlled thereby, and means in said first valve mechanism for maintaining said fluid pressure operated locking means active.

during a portion of the cycle of operation of the first fluid motor.

4. In a hydraulic system, a source of fluid pressure; a plurality of fluid motors; control valve mechanism for each of said motors, said control valve mechanisms being connected in series in said system; fluid directing means in the first valve mechanism in said system, said fluid directing means being responsive to fluid pressure to initiate a cycle of operation of the motor controlled by said first valve mechanism, each valve mechanism being operative upon the conclusion of a cycle of operation of the motor controlled thereby, to prevent further operation of such motor and direct all fluid supplied thereto to the next succeeding valve mechanism; and means in the final valve mechanism responsive to fluid pressure to apply fluid to the fluid directing means in the first valve mechanism to initiate operation of the fluid motor controlled thereby.

5. In a hydraulic system, a source of fluid pressure; a plurality of fluid motors; control valve mechanism for each of said motors, said control valve mechanisms being connected in series in said system; flow directing means in the first valve mechanism operated by fluid pressure to initiate a cycle of operation of the fluid motor controlled thereby and operative to direct fluid from said source to the second valve mechanism in said system upon the completion of a cycle of operation of the first fluid motor; means operated by the fluid motor controlled by said second valve mechanism to discontinue the operation of said second motor and direct fluid from the first valve mechanism to the third valve mechanism in said system; fluid directing means in said third valve mechanism, said last mentioned fluid-directing means being operative to cause a cycle of operation of the fluid motor controlled by said third valve mechanism; and means in said third valve mechanism responsive to fluid pressure and the final stage of a cycle of operation of said third fluid motor to apply fluid pressure to the flow-directing means in said first valve mechanism to initiate the next cycle of operation of said first fluid motor.

6. In a hydraulic system, a source of fluid pressure; a reversible fluid motor; pressure responsive valve means between said source and motor to control fluid flow from said source to cause consecutive forward and reverse operation and idle periods of said motor; a second fluid motor; control valve means for said second motor, said first-mentioned valve means directing fluid from said source to the control means for said second motor during idle periods of the first-mentioned motor; a third fluid motor; and a third control valve mechanism between the control means for said second motor and said third motor; said second control valve means directing fluid to said third control valve during idle periods of said second motor, said third control valve mechanism directing fluid to said third motor to cause forward and reverse operation thereof and to the first-mentioned valve means at the completion of a cycle of operation of said third motor to initiate operation of said first-mentioned fluid motor.

7. In a hydraulic system, a source of fluid pressure; a plurality of fluid motors; a control mechanism for each of said motors, said control mechanisms being connected in series in said system; flow-control means in said control mechanisms for varying the rates of operation of said fluid motors during the respective cycles of operation thereof; flow-directing means in each con-

trol mechanism for causing the motor to perform one complete cycle of operation, said flow-directing means then directing fluid to the next control mechanism to initiate the operation of the motor controlled thereby, said flow directing means rendering said flow control means inoperative when fluid is being directed to the succeeding control mechanism, the flow-directing means of the final control mechanism in said series directing fluid to the first control mechanism to initiate operation of the first fluid motor at the conclusion of a cycle of operation of the final motor in said series.

8. In a hydraulic system, a source of fluid pressure; a plurality of fluid motors at least two of which are of the piston and cylinder type; a control mechanism for each of said motors, said control mechanisms being connected in series in said system; fluid directing means in said control mechanism, said fluid-directing means being operative to cause a complete cycle of operation of the motor served by the respective control mechanism and then direct fluid to the next succeeding control mechanism, the fluid directing means in the final control mechanism in said system directing fluid to the first control mechanism in the series to initiate operation of the first fluid motor; and means in the control mechanisms for the motors of the piston and cylinder type for repeatedly actuating the fluid directing means of such control mechanism at the termination of the working strokes of the pistons to cause the latter to execute a plurality of reciprocations of a length less than the usual strokes of the pistons.

9. In a hydraulic system, a source of fluid pressure including a pump and reservoir; a plurality of fluid motors; a control valve mechanism for each fluid motor, each of said control valves having an inlet and a pair of outlets; means connecting one outlet of each valve with said reservoir, the first valve in said system having a control port; means connecting the inlet of the first valve with said pump and the second outlet of each valve with the inlets of succeeding valves, the second outlet of the final valve in said system being connected with the control port of said first valve; and means in each valve for directing fluid supplied to the inlet thereof to the fluid motor controlled by such valve to cause one cycle of operation thereof, said means directing the exhaust from said motor to the reservoir, said means directing fluid supplied to the valve at the conclusion of the operation of the motor to the second outlet to be conducted to the inlet of the succeeding valve, fluid supplied to the control port of the first valve being applied to the flow directing means thereof to place the same in position to initiate operation of the first fluid motor and a cycle of operation of the system.

10. In a hydraulic system, a source of fluid pressure including a pump and reservoir; a plurality of fluid motors; a control valve mechanism for each fluid motor, each of said control valves having an inlet and a pair of outlets, the first of said valves having a control port; means connecting one outlet of each valve with said reservoir; means connecting the inlet of one valve with said pump and the second outlet of each valve with the inlets of succeeding valves, the second outlet of the last valve in the system being connected with the control port of the first valve in said system; means in each valve for directing fluid supplied to the inlet thereof to the fluid motor controlled thereby to cause a

complete cycle of operation of said motor, said means directing the exhaust from said motor to the reservoir; means in said control valve mechanism operative during the operation of said motor to by-pass a portion of the fluid supplied to the respective control valve mechanism, to the reservoir to reduce the speed of operation of the motor, said means directing all fluid supplied to the valve at the conclusion of the operation of the motor, to the second outlet to be conducted to the inlet of the succeeding valve, fluid supplied to the control port of the first valve being applied to the flow directing means thereof to place the same in position to initiate operation of the first fluid motor and a cycle of operation of the system.

11. In a hydraulic system, a source of fluid pressure; a plurality of fluid motors; a control mechanism for each of said motors, said control mechanisms being connected in series in said system; flow-directing means in each control mechanism, said flow-directing means being operative to cause the motor controlled by the control mechanism to perform one complete cycle of operation and then to direct fluid to the next control mechanism to initiate the operation of the motor controlled thereby, the flow-directing means of the last control mechanism in said series directing fluid to the first control mechanism to initiate operation of the first fluid motor at the conclusion of a cycle of operation of the last motor in said system.

12. In a hydraulic system, a source of fluid pressure; a pair of fluid motors; a control mechanism for each of said motors, the first of said control mechanisms receiving fluid directly from said pressure source and the other receiving fluid from said first control mechanism; and flow-directing means in each control mechanism, said flow-directing means being operative to direct fluid to the motor controlled by the respective control mechanism to cause a complete cycle of operation thereof, and then direct fluid to the other control mechanism to initiate the operation of the motor controlled thereby.

13. In a hydraulic system, a source of fluid pressure; a pair of fluid motors; a control mechanism for each of said motors, the first control mechanism receiving fluid directly from said pressure source and the second receiving fluid from said first control mechanism; pressure-responsive flow-directing means in each control mechanism, said flow-directing means being operative to direct fluid to the motor controlled by the respective control mechanism to cause it to perform a complete cycle of operation; and means in the second control mechanism operative at the conclusion of a cycle of operation of the second motor to apply fluid to the pressure responsive flow-directing means of the first control mechanism to initiate a cycle of operation of the first motor.

14. In a hydraulic system, a source of fluid pressure; a first fluid motor; a first control mechanism between said motor and said pressure source and receiving fluid from the latter; a second fluid motor; a second control mechanism between said second fluid motor and said first control mechanism and receiving fluid from the latter; and pressure-responsive flow-directing means in said second control mechanism, said flow-directing means including first and second elements, the latter being normally disposed to apply fluid flowing to the second control mechanism to the first element to move the same to a

position to initiate a cycle of operation of said second fluid motor, said second element being responsive to fluid pressure during the operation of said second fluid motor to move to a position to direct fluid supplied to said second control mechanism back to said first control mechanism to initiate a succeeding cycle of operation of the system.

15. Mechanism for controlling a fluid motor comprising a body with inlet, forward and reverse motor and first and second outlet ports; first and second pressure responsive flow-directing elements disposed for movement in said body, the first of said elements being normally disposed in position to apply fluid from said inlet to the second element to move the same to a position to direct fluid from said inlet port to the forward motor port and from the reverse motor port to the first outlet port; means in said body operative when the forward operation of the motor controlled by the mechanism ceases, to shift said second element to a position to direct fluid from said inlet port to the reverse motor port and from the forward motor port to the first outlet port; and means in said body for applying fluid pressure during the reverse operation of said motor, to said first flow-directing element to shift and hold the same in position to connect the inlet port with said second outlet port.

16. Mechanism for controlling a fluid motor comprising a body with inlet, forward and reverse motor and first and second outlet ports; first and second pressure responsive flow-directing elements disposed for movement in said body, the first of said elements being normally disposed in position to apply fluid from said inlet to the second element to move the same to a position to direct fluid from said inlet port to the forward motor port and from the reverse motor port to the first outlet port; means in said body operative when the forward operation of the motor controlled by the mechanism ceases, to shift said second element to a position to direct fluid from said inlet port to the reverse motor port and from the forward motor port to the first outlet port; means in said body for applying fluid pressure during the reverse operation of said motor, to said first flow-directing element to shift and hold the same in position to connect the inlet port with said second outlet port; and means in said body operated by said motor during the final stage of reverse operation thereof to interrupt fluid flow from said inlet port to said reverse motor port.

17. Mechanism for controlling a fluid motor comprising a body with inlet, forward and reverse motor and first and second outlet ports; first and second pressure responsive flow-directing elements disposed for movement in said body, the first of said elements being normally disposed in position to apply fluid from said inlet to the second element to move the same to a position to

direct fluid from said inlet port to the forward motor port and from the reverse motor port to the first outlet port; means in said body operative when the forward operation of the motor controlled by the mechanism ceases, to shift said second element to a position to direct fluid from said inlet port to the reverse motor port and from the forward motor port to the first outlet port; means in said body for applying fluid pressure during reverse operation of said motor, to said first flow-directing element to shift and hold the same in position to connect the inlet port with said second outlet port; means in said body operated by said motor during the final stage of reverse operation thereof to interrupt fluid flow from said inlet port to said reverse motor port; and means in said body for shifting said first flow-directing element back to the position to apply fluid from said inlet port to said second flow-directing element, the last-named shifting means becoming operative after reverse operation of said motor has ceased.

18. Mechanism for controlling a fluid motor comprising a body with inlet, forward and reverse motor and first and second outlet ports; first and second pressure-responsive flow-directing elements disposed for movement in said body, the first of said elements being normally disposed in position to apply fluid from said inlet to the second element to move the same to a position to direct fluid from said inlet port to the forward motor port and from the reverse motor port to the first outlet port; spring means in said body operative to shift said second element to a position to reverse the inlet, forward and reverse motor and outlet port connections when the forward operation of the motor controlled by said mechanism ceases; orifice means for resisting fluid flow occurring only during reverse operation of said motor to create a pressure differential; means for applying the higher pressure of said differential to said first flow-directing element to shift the same to a position to connect said inlet with said second outlet port; means operated by said motor during the final stage of reverse operation thereof to interrupt fluid flow between said inlet port and said reverse motor port; and spring means for shifting said first flow-directing element back to the normal position thereof upon the dissipation of said pressure differential due to the stopping of said motor.
